REINFORCED SEPARATING END STOP FOR A SLIDE FASTENER

Alfred E. Carlile, Meadville, Pa., assignor to Talon, Inc.,
a corporation of Pennsylvania

Filed Dec. 21, 1964, Ser. No. 83,107

Term of patent 14 years

(Cl. D17—8)

FIG. 1 is a plan view of a reinforced separating end stop for a slide fastener showing my new design;

FIG. 2 is a rear view thereof;

FIG. 3 is a bottom end view thereof;

FIG. 4 is an enlarged plan view thereof with the stop in separated condition; and

FIG. 5 is a cross-sectional view thereof taken along line 5—5 of FIG. 4.

The broken line showing of stringer tapes and slider for a slide fastener is for illustrative purposes only.

I claim:

The ornamental design for a reinforced separating end stop for a slide fastener, substantially as shown and described.
